COMPOSITION FOR PREVENTING VAPOR
LOCK IN INTERNAL COMBUSTION EN-
GINES

John Howard Essick, Erie, Pa.

No Drawing. Application August 20, 1935,
Serial No. 37,098

1 Claim. (Cl. 44-9)

This invention relates to compositions for use in internal combustion engines and pertains particularly to a composition designed to be introduced into the engine with the fuel.

5 In the operation of those motor vehicles which are required to cover relatively great distances and which are kept in constant use, such as trucks and passenger carrying buses, considerable difficulty is had and time lost through the 10 development of a condition known as vapor lock. This condition is brought about by the heating up of the engine to the point where the fuel passing through the carburetor is converted in the carburetor from a spray to a vapor which 15 by expansion therein chokes the passage to the intake manifold of the engine and thus prevents the engine receiving the required amount of fuel for its continued satisfactory operation. When this condition develops the only remedy 20 at the present time is to stop the motor and allow the same to cool down.

The present invention has for its primary object to provide a composition which will prevent the development of the vapor lock condition by 25 introducing into the engine through the fuel supply means, substances which are so combined as to lubricate the contacting surfaces of moving parts such as valve stems, piston rings, and the like and maintain the engine temperature 30 below the point which is conducive to the development of the vapor lock condition above referred to.

Another object of the invention is to provide a composition which, in addition to functioning 35 in the manner above described, will facilitate the removal of carbon from the interior of the cylinder when the use of the composition is begun and which will then operate to prevent the development of carbon.

40 The present composition consists of the following ingredients combined in the appended approximate proportions necessary for the making of a fifty gallon batch of the product.

Kerosene.....	gallons	27	ounces	44
Oil of mirbane (U. S. P.)	gallons	5	ounces	60
Oil of creosote (U. S. P.)	gallons	10	ounces	120
Turpentine.....	gallons	2	ounces	44
Oil of cedar wood.....	gallons	2	ounces	44
Camphorated oil.....	gallon	1	ounces	72

50 The foregoing ingredients are mixed preferably by adding the oil of creosote and oil of mirbane to the kerosene and then adding the turpentine, oil of cedar wood and camphorated oil 55 in the order named. By this procedure a clear solution results whereas, if any other order of mixing is followed, the product is cloudy and unsatisfactory in appearance.

The composition is used by adding approximately one ounce to each four gallons of gasoline. It is thus fed into the motor vehicle engine with the fuel through the carburetor and in this way it is brought into intimate contact with the valves and the stems and with the walls of the engine cylinder where it will work its way down between the same and the piston rings.

5 Experiments with the composition have shown that with the constituents used in the proportions set forth, the kerosene will burn out and remove any carbon deposits which may be present in the engine cylinders and the other oils adhere to the metal parts and are only eliminated by a wearing out process and during this 10 time they function to keep down excessive development of heat. It will thus be apparent that by the elimination of the carbon the cylinders 15 will remain clean and the proper even contact of the piston rings with the cylinder walls will 20 not be interfered with and the working of the oils in between the contacting surfaces permit 25 the same to move without friction and consequently without the development of heat. Also, because of the free movement of the piston rings 30 relative to the cylinder walls, a substantially 35 perfect seal is maintained which prevents the loss of power.

The proportioning of the ingredients enumerated, in the amounts specified, makes it possible 30 to attain the desired results without the development of smoke or the deposit of gum in any 35 of the engine parts. It is particularly essential that the camphorated oil be held to approximately the amount specified so that this condition of smokiness and gumminess will not be 40 brought about.

While it is probable that some variations may be made in the amounts of the other ingredients, it is necessary that the quantity of camphorated oil specified for a fifty gallon batch be 45 used in order that no gummy deposit will be left or smoke developed.

I claim:—

A composition to be added in small amounts 45 to hydrocarbon internal combustion engine fuel for eliminating vapor lock conditions in internal combustion engines consisting of the following ingredients taken in the appended approximate proportions for the production of a fifty gallon 50 batch:

Kerosene.....	gallons	27	ounces	44
Oil of mirbane (U. S. P.)	gallons	5	ounces	60
Oil of creosote (U. S. P.)	gallons	10	ounces	120
Turpentine.....	gallons	2	ounces	44
Oil of cedar wood.....	gallons	2	ounces	44
Camphorated oil.....	gallon	1	ounces	72

JOHN HOWARD ESSICK.
